UNITED STATES PATENT OFFICE

2,671,455

DISHWASHER

John MacDonald and George R. Meadowcroft,
Jackson, Mich., assignors to Lake State Products, Inc., Jackson, Mich., a corporation of Michigan

Application December 29, 1945, Serial No. 638,273

9 Claims. (Cl. 134—57)

1

The present invention relates to improvements in fully automatic dishwashers.

Automatic dishwashers for home use have been an active subject for investigation for many years. Of the multitude proposed only a few have reached the consumer. Those that have been placed in production have been relatively expensive and beyond the means of the average person. Another factor that has restricted the general acceptance and use of such devices has been their limited cleaning capacity, which has necessitated precleaning of the dishes to a considerable extent before placing the dishes in the device. This precleaning has been necessitated by the inability of the device to remove certain food particles and the tendency of the food particles unless removed to accumulate and clog the drain system. Further, devices on the market at this time do not perform the drying operation as well as desired, especially with respect to glasses and silverware.

According to the present invention, both the washing and drying operations in an automatic dishwasher have been substantially improved through the provision of a source of extremely hot water available in required quantities throughout the cycle of operation. To improve the self-cleaning of the vat and avoid accumulation of food particles in and about the drain system, the drain for the system is in the form of a sump concentric with and surrounding the impeller shaft with a valve likewise concentric with and surrounding the impeller shaft, controlling the drainage from the vat into the sump. Other improvements in venting, regulation of washing and rinsing water, and control of the cycle of operations has contributed to the improved performance, ease of operation, and cost of construction.

Thus one of the objects of the present invention is to provide an improved dishwasher, fully automatic in operation.

Another object is to provide novel means for heating, supplying and metering water in automatic dishwashers.

Another object is to provide an automatic dishwasher having improved arrangements for venting the steam to assure the complete drying of the dishes and silverware at the end of the washing and rinsing cycle.

Another object resides in the improvements for the control of the lid of the vat.

Another object is to provide a fully automatic and novel structure for operating the drain valve of an automatic dishwasher.

A still further object of the invention is to provide an automatic dishwasher in which the drain

2

valve is opened and closed with the starting and stopping of the impeller motor.

A still further object of the invention is to provide a fully automatic dishwasher which is of efficient operation, designed to be inexpensively manufactured, and capable of being used for long periods without appreciable maintenance.

These and other objects and advantages residing in the combination, construction and arrangement of parts, the cycle of operation and other details associated with the controls and associated automatic features of the device will become apparent from a consideration of the following specification and appended claims.

In the drawings,

Fig. 1 is a perspective view of an automatic dishwasher embodying the principles of construction of the present invention, with the outer casing broken away to show the interior structure,

Fig. 1a is a fragmentary detail of the lid or cover hinge,

Fig. 2 is a vertical cross-sectional view through the vat and a portion of the structure associated with the motor and impeller.

Fig. 2a is a detail of the latch release structure the figure being a plan of this structure as seen in Figure 2,

Fig. 3 is a diagrammatic layout of the electrical circuit and associated parts,

Fig. 4 is a bottom view of the timer mechanism partly shown in broken cross section,

Fig. 5 is a cross-sectional view taken on line V—V of Fig. 4, and

Figs. 6 and 7 are fragmentary perspective views of certain details of construction of the timer mechanism.

Referring to the illustrated form of the invention, a fully automatic dishwasher is disclosed as comprising a suitable framework 10, supporting the vat 12, which consists of a cylindrical portion 14, and a frustrated conical portion 16. The vat 12 and associated structure are enclosed by suitable side panels 18. The top panel 20 has a back portion 22 and an opening 24 within which the lid hinge or cover 26 operates.

Referring to Fig. 2, the vat 12 has been illustrated with all supporting structure for dishes and silverware removed for greater clarity of the remaining structure. Enclosing the opening 28 in the conical bottom portion 16 of the vat 12 is the casting 30 having an annular flange 32 and held in position by screws 34. A suitable gasket, not shown, will be employed to prevent leakage between the joints between the casting 30 and the conical bottom portion 16.

As illustrated, the casting 30 defines a sump 36 as well as a supporting framework 38 for the motor 40. The motor shaft 42 drives the outer sleeve 44 which in turn drives the shaft 46 having the impeller 48 for washing and rinsing water removably connected to its upper end through a screw 50. The position of the impeller 48 on the shaft 46 is determined by a cross pin 52 which engages in a recess 54 and acts also as a driver for the impeller 48.

The centrifugal actuator for the drainage valve and the control of the lid 26 for venting the vat 12 comprises lateral ears 56 to which heavy arms 58 are pivoted to function as flyball governors. At the upper end of the arms 58 are pivotal connections 60 with links 62 having pivotal connections at 64 attached to a sleeve 66 having a free sliding and rotatable fit with respect to the upper end 68 of the sleeve 44 carrying the lateral ears 56 and connected for rotation with the motor shaft 42. A compression spring 70 holds the centrifugal governor unit in the extended full line position shown in Fig. 2 by engaging with a shoulder 72 of the sleeve 66. As will be readily understood rotational forces will cause the centrifugal governor unit to assume the dotted line position shown in Fig. 2, which will lower the sleeve 66 while the motor 40 is being run.

The valve mechanism for controlling drainage between the vat 12 and the sump 36 preferably takes the form of a poppet valve 73 having an annular flange 74 grooved to receive a soft rubber sealing ring 76 or other equivalent structure. The ring 76 is shown sealing against a conical surface 78 in the casting 30. The structure defining the sump 36 comprises an integral central and vertically extending socket 80 through which the impeller shaft 46 extends freely and with respect to the inner surface of which socket 80 a tube 90 is mounted for vertical reciprocation, this tube resting at its lower end upon a collar 92, itself resting upon the upper end of the sleeve 66, through the medium of a wear washer 94, and the tube 90, at its upper end, having a ring cap 84 secured thereto. This ring cap provides a gland bushing 84a, which has sliding sealing contact with the impeller shaft 46, and an annular end flange 84b, integral with the bushing part 84a and extending at its outer periphery into an annular recess formed between an inner sleeve 82 and an outer sleeve 82a both of which are connected to be rigid with one another and combine to form the upstanding sleeve part of the drain valve 73. This valve sleeve part has a rigid annular flange 82b at the upper end, which has a sliding fit with the impeller shaft 46 and by means of which flange 82b the drain valve as a whole is supported upon the top of the reciprocable tube 90 by engagement with the said end flange 84b.

The construction and arrangement is such that when the motor shaft 42 is at rest and the centrifugal governor is accordingly in the extended condition, as shown in full lines in Figure 2, the collar 92 and hence the tube 90 will be in an elevated position, in which the drain valve is held open as shown in the full lines in Figure 2. When, however, the motor shaft is rotated and the centrifugal governor is moved to the collapsed condition as shown by the dotted lines the collar 92, and hence the tube 90, will be lowered and thereby cause the drain valve also to be lowered and moved into the closed position as shown in dotted lines in Figure 2. The tube 90 is readily

slidable for axial movement within the sleeve 66 and as stated is fixed at its lower end to a collar 92 having clearance with the shaft 46 and resting upon the sleeve 66 and spaced therefrom by a wear washer 94.

To hold the collar 92 against rotation, slots 96 are provided upon opposite sides thereof to receive the forked ends 98 of the lever 100. The lever 100 is pivotally supported on the pin 102 carried on the bracket 104 with an extension 106 of the lever 100 carrying an adjustable stop in the form of a bolt 108. Also pivoted on the pin 102 alongside the lever 100, is a lever 110 having an extension 112 which is bent laterally to lie in the plane of the lever 100 as shown in Figure 2a. A narrow gap 114 is provided between the lever 100 and the extension 112 into which under certain operating conditions the enlarged head 116 of a pin 116 is projected to permit rocking action of the lever 100 to be transferred to the lever 110. As will be more fully described hereinafter, the pin 116 is under the control of the timer mechanism for the regulating cycle of operation of the dishwasher. A rod 118 is connected at one end to the lever 110 and at the opposite end to the latch 120, which in the position shown in Fig. 2 will project through the opening 122 to hold the lid 26 closed. A hand opening is indicated at 124 to permit engagement with the spring plunger 126 for projecting the latch 120 out of the opening 122 for opening the lid. The spring 128 continuously stresses the lever 110 in a counterclockwise position to hold the latch 120 in position to engage the catch of the cover 26.

The arrangement for providing at all times an adequate supply of extremely hot water comprises an inlet 130 from a suitable source of cold water under pressure, as for example the conventional municipal water supply. The cold water is directed into a heavily insulated hot water heating tank 132, which is preferably provided with an electric heating element 134 and a standard thermostat 136. A heavily insulated tank of approximately two to three gallons capacity will assure an adequate supply of extremely hot water at all times. As the heavy insulated heater tank 132 will have very little heat loss, it is not uneconomical to have this storage of hot water at all times although the dishwasher is used only two or three times each day at the most. The tank 132 is under full line pressure at all times with the result that the cold water flows into the tank at the same rate the hot water is drawn from the tank. The electric heating element 134 is of relatively large capacity so that the water stored in the tank 132 may be rapidly heated to the order of 180° F. in a very few minutes so as to provide the necessary hot water within the cycle of operation. The outlet 138 withdraws the water from the tank 132 from the top. The water flows through a solenoid valve 140 past the pressure reducing valve 142 and through the electrically controlled inlet valve 144 to be discharged into the vat 12 through the connection 146. The connection 146 of the vat 12 is preferably in the form of a metering jet which with the pressure regulated by the valve 142 will admit into the vat 12 a certain volume of hot water within a predetermined time interval. Drainage from the vat 12 is through drain connection 148 connecting with the lower level of the sump 36.

The structure for moving and holding the lid 26 in the full line position shown in Fig. 2 is

illustrated in Fig. 1a. As shown the lid 26 has a hinge bracket 150 which with a bracket 152 and a pin 154 forms a piano hinge of known construction. Also, on the pin 154 is a torsion coiled spring 156 having its ends 158 acting outwardly against the brackets 150 and 152. When the lid 26 is closed as shown in Fig. 1a, the spring 156 is stressed. When the lid 26 is released by the latch 120, the tension in the spring 156 will raise the lid 26 to the venting position shown in Fig. 2.

For controlling the automatic cycle of operation of the dishwasher, a suitable timer mechanism is required. Preferably, the timer is provided with an electric motor for supplying the energy for driving the timer during the cycle of operation. In the illustrated form the timer comprises a bracket 158 supporting an electric motor 160 for slowly rotating through suitable gearing 162 a cross shaft 164. To permit the shaft 164 to be rotated in a forward direction independently of the motor 160, a conventional ball or pin free wheeling clutch 166 is provided between the gearing 162 and the shaft 164. Thus the shaft 164 may be rotated by the motor 160 in the direction of the arrow of Fig. 6 at a slow speed and it also may be manually rotated or advanced at a more rapid speed in the same direction.

The manual means of operation of the shaft 164 comprises a coupling 168 located between the shaft 164 and the shaft 170 upon which is a sprocket 172 driven by a chain 174 running over a sprocket 176 on a dial shaft 178. A pointer knob 180 is secured to the shaft 178 and sweeps a dial 182 having the station of operation indicated, namely, "Off," "On," "Wash," "Rinse," and "Dry."

Rotated by the shaft 164 is cam 184 for operating pin 116. (See Fig. 2a.) A spring 186 holds the pin 116 against the cam 184 and retracts the pin 116 after it has been projected by the lobe 188 into the bite between the lever 100 and the extension 112 to cause the latch 120 to be rocked upon stoppage of the motor 40 to release the lid 26 to a venting position. The outer end 190 of the pin 116 is normally positioned in the plane of the lever 100. A reduced portion 192 of the pin 116 has clearance in an opening 194 in the bracket 104 for slight lateral movement produced by the movement of the lever 100. When the end 190 is projected into the plane of the extension 112, while still in the plane of the lever 100, it becomes a solid link between these parts and the clockwise movement of the lever 100 is transferred to the lever 110 to actuate the latch 120.

Referring to the schematic lay out of the electrical circuit shown in Fig. 3 which also illustrates the relationship between the timer structure and the elements controlled thereby, a standard wall plug is indicated at 196 for connecting the dishwasher to any household electrical circuit, with the lead in conductors indicated at 198 and 200. It will be noted that the connecting of the plug 196 into the household circuit will close the circuit in which the electric heater 134 is located through the conductors 202 and 204. The thermostat 136 is shown inserted in the conductor 204 to open and close the heater circuit depending upon the temperature of the water within the heater 132. It is to be understood from the arrangement illustrated that the hot water heater 132 is connected at all times to assure a supply of extremely hot water for use whenever it is desired to operate the dishwasher.

The electrical circuit for the impeller motor 40 includes the conductor 206 connecting with the make and break switch 208 connected with the common conductor 210. In a similar manner the electrical circuit for the inlet valve 144 comprises the conductor 212 connecting with the switch 214 which is in turn connected with the common conductor 210. The circuit for the operation of the timer motor 160 comprises a conductor 216 connecting the timer motor 160 in series with the switch 218 which in turn is connected on one side with the common conductor 210. Also in series with the switch 218 is a signal light 220 having a conductor 222 with a common connection with the conductor 216. To facilitate the assembly and replacement of the timer and its associated circuits, a connector plug 224 is provided which enables a plug in connection to be made between the timer and its associated switches and the remaining electrical circuits controlling the inlet valve 144, the impeller motor 40 and the signal light 220.

The mechanism for controlling the operation of the switches 208, 214 and 218 comprises a cam member 226 on and rotated by the shaft 164 driven by the timer motor 160. The switches 208, 214 and 218 may be of similar construction and preferably each comprises a pair of spaced arms 228 and 230 clamped in a support 232 of insulating material. Preferably the arms 228 and 230 are so arranged and clamped that both of them are stressed in the same direction and toward the outer surface 234 of the cam 226. The electrical circuit is closed through the engagement of the contacts 236 mounted on the opposed sides of the resilient arms 228 and 230.

The cam 226 on opposite sides is provided with pairs of annular track portions 238 and 240, which are spaced similarly to the spacing of the turned and offset ends 242 and 244 of the arms 228 and 230. The cam 226 is rotated in the direction indicated by the arrows in Figs. 6 and 7. It thus follows that the inclined portions 246 and 248 will cause the cam follower portions 242 and 244 to ride up the incline, and it will also be noted that the track 240 is abruptly terminated at 250 while the track 238 is abruptly terminated at 252.

As heretofore stated the spring arms 228 and 230 are continuously urged toward the cam 226. When rotation of the cam 226 causes the end 244 to drop off the end 250 of the track 240, the contact 236 on the arm 228 is biased toward the cam 226 to separate the contacts 236, as shown in Fig. 7, to open the circuit. Thereafter rotation of the cam 226 to the point at which the end 242 drops off the end 252 of the track 238 will result in movement of the arm 230 toward the cam 226 to bring the contacts 236 together to close the circuit. Continued rotation of the cam 226 then brings the ends 242 and 244 up the inclined portion 246 upon the crest of the tracks 238 and 240 with the circuit remaining closed.

It should be apparent to those skilled in the art that the contacts 236 will open and close with snap action and that with the arrangement described the circuit in which the contacts 236 are located can be opened and closed one or more times during the cycle of operation of the cam 226. It will be understood that the remaining circuits may be controlled by the cam 226 in the manner described with reference to that specifically illustrated in Figs. 6 and 7.

To summarize the operation and cycles of operation controlled by the timer motor 160, the

dishwasher unit herein illustrated is designed to be connected in the usual manner to a cold water or hot water supply and to the sewer. In actual operation the dishwasher will be permanently plugged into a standard household electrical outlet, to assure at all times the availability of a tank of extremely hot water under the control of the thermostat 136. When it is desired to use the dishwasher, the cover 26 is raised and the dishes are loaded in suitable racks, not shown. The cover is then moved into its latched position, shown in dotted outline in Fig. 2, and the knob 180 is manually turned to the "on" position, which results in rotation of the shaft 170, advancing the cam 226 to close the switch 118 located in the timer circuit causing the timer motor 160 to operate. Thereafter the timer motor 160 takes over the rotation of the cam 226. Preferably the initial function of the timer motor 160 is to advance the cam 226 sufficiently to close the switch 208 in the impeller motor circuit to cause the impeller motor 40 to rotate the impeller 48, and at the same time through the action of the centrifugal unit associated with the impeller motor 40 to lower and close the drain valve 72. The operation of the motor 40 has the additional function of exerting an upward thrust on the rod 118 to hold the latch 120 in a position resisting any attempt to open the lid 26 with the motor 40 running.

With the valve 72 closed, the timer motor 160 will advance the cam 226 sufficiently to close the switch 214 in the inlet valve circuit to open the valve for a predetermined period to admit a measured quantity of water to the vat 12. At the end of the initial washing cycle, which is determined by the design and rotation of the cam 226, the switch 208 is opened and the motor 40 stopped, permitting the spring 70 to lift the valve 72 from its seat to drain the washing water from the vat 12. Thereafter the switch 208 is closed and the motor 40 is started and the valve 72 is closed. Following this action the inlet valve switch 214, which was opened through rotation of the cam 226 after a predetermined amount of washing water has been admitted, is again closed to admit a predetermined quantity of rinsing water into the vat 12. At the end of the rinsing cycle the pin 116 is advanced by the cam 184 between the lever parts 100 and 112 with the result that when the cam 226 opens the impeller motor switch 208, stopping the motor 40, the action of the spring 70 results in a downward pull upon the rod 118 against the action of the spring 128, which therefore swings to urge the latch 120 outwards into its releasing position, with respect to the plunger 126, thereby permitting the cover 26 to assume the steam venting position shown in full outline in Fig. 2.

After the rinse water has drained past the valve 72, the impeller motor circuit is again closed by closing the switch 208 through the action of the cam 226 and the impeller 48 is operated over a predetermined period to assist in drying the dishes. The timer 160 continues to rotate the cam 226, and after a predetermined period the impeller motor circuit is opened by opening the switch 208, stopping the motor 40. At the same time advancement of the cam 184 has carried the lobe 188 beyond engagement with the pin 116, which has been withdrawn by the spring 186, to the inoperative position shown in Fig. 2a. The timer motor 160 has now approached the end of its cycle of operation and shuts itself off through advancement of the cam

226. This completes the cycle of operation during which time the heater 134 in the water tank 132 has completely recovered and has available for the next cycle of operation of the dishwasher an adequate supply of extremely hot water. The cycle of operation can be repeated indefinitely.

Having thus described our invention, what we claim as new and desire to cover by Letters Patent is:

- 10 1. A dishwasher comprising a vat, a liquid impeller in said vat, a motor for driving said impeller, a valve for draining said vat, and a centrifugal actuator driven by said motor and operatively connected to said valve for closing said valve when the motor is started.
- 15 2. A dishwasher comprising a vat, a central drain structure in said vat, a vertical agitator shaft extending through said structure, a valve seat defined in said structure and surrounding said shaft, a valve, means supporting said valve for movement relative to said seat, a motor for driving said shaft, and an operative connection between said motor and said valve including rotational responsive means to open and close said valve upon stopping and starting of said motor.
- 20 3. A dishwasher comprising a vat, having a central opening in the bottom thereof, a drain structure closing said opening, a vertical agitator shaft concentrically supported in said drain structure, a valve seat in said structure and concentric with said shaft, a valve concentric with said shaft and supported for vertical movement relative to said seat to control the drainage of liquid from said vat, a motor for said shaft, rotational responsive means actuated by said motor, and an operative connection between said means and said valve for raising and lowering of said valve upon stopping and starting of said motor.
- 25 40 4. In an automatic dishwasher, a washing and rinsing chamber, an agitator for washing and rinse water located in said chamber, a motor for said agitator located outside of said chamber, a drain for said chamber, a valve for controlling said drain, mechanical means energized by said motor for operating said valve, a mechanical connection between said means and said valve to open said valve upon motor stoppage and to close said valve upon motor startage, and means for stopping and starting said motor to simultaneously control the agitation of water in said chamber and the drainage of water therefrom.
- 45 5. In an automatic dishwasher, a vat, a drain for said vat, a washing and rinsing water circulator in said vat, a supply of hot water connected with said vat, an operative connection between said drain and said circulator to open and close said drain including rotational responsive means, a timer, means under the control of said timer to start and stop said circulator to open and close said drain, a valve for regulating the flow of hot water from said supply to said vat, and means under the control of said timer to open said valve for a predetermined period after said circulator is started and said drain is closed.
- 60 6. An automatic dishwasher comprising a circulator, a motor for said circulator, a centrifugal actuator rotatable by said motor, a drain valve, and an operative connection between said actuator and said valve.
- 65 7. In an automatic dishwasher, a vat, intermittently operable circulator means for directing cleansing liquid against articles placed in said vat, a supply of cleansing liquid connected to
- 70 75

said vat, drain mechanism for said vat including means responsive to centrifugal forces for retention of cleansing liquid in said vat, a motor for actuating said means, an operative connection between said motor and said drain mechanism, means for controlling the intermittent operation of said motor and said first means, and means acting upon said drain mechanism for draining said vat substantially concurrently with the stoppage of said motor and said first means.

8. In an automatic dishwasher, a vat, circulator means located in said vat for intermittently directing cleansing liquid against articles placed in said vat, a drain opening defined in the base of said vat, means responsive to centrifugal forces preventing flow of liquid into said opening during periods of operation of said first means, a timer, means under the control of said timer for initiating and stopping the operation of said first means, and means under the control of said timer for rendering said centrifugal responsive means inoperative and to thereby effect draining to said vat through said drain opening, said last means acting upon said centrifugal responsive means substantially concurrently with the stoppage of said first means whereby drainage of cleansing liquid from said vat through said drain opening takes place during a period of arrested cleansing liquid in said vat.

9. In an automatic dishwasher, a vat having a drain opening in the base thereof, drain mechanism for controlling the draining of cleansing liquid into said drain opening including means responsive to centrifugal forces for the reten-

tion of cleansing liquid in said vat, an intermittently rotated impeller disposed in said vat for agitating the cleansing liquid therein, a motor for rotating said impeller, an operative connection between said motor and said drain mechanism, timer means for controlling the intermittent operation of said motor and impeller, and means acting upon said drain mechanism for draining said vat substantially concurrently with the stoppage of said motor and impeller by said timer means.

JOHN MACDONALD.
